Primary Examiner — Keith J Wilson*Assistant Examiner* — Carolyn W Davis(74) *Attorney, Agent, or Firm* — KIRTON McCONKIE;
 Evan R. Witt(57) **CLAIM**

The ornamental design for a ventilator frame as shown and described.

DESCRIPTION

FIG. 1 is a perspective view of a ventilator frame showing our new design;

FIG. 2 is another perspective view thereof;

FIG. 3 is another perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof;

FIG. 9 is a bottom plan view thereof;

FIG. 10 is a perspective view of the ventilator frame showing our new design, wherein a motor is disposed in the ventilator frame; and,

FIG. 11 is another perspective view of the ventilator frame showing our new design, wherein the motor is disposed in the ventilator frame.

The broken lines illustrate portions of the ventilator frame and form no part of the claimed design.
